UNITED STATES PATENT OFFICE.

KENNETH E. STUART, OF PHILADELPHIA, PENNSYLVANIA.

PNEUMATIC-DESPATCH SYSTEM.

SPECIFICATION forming part of Letters Patent No. 744,814, dated November 24, 1903.

Application filed June 10, 1902; Serial No. 110,972. (No model.)

To all whom it may concern:

Be it known that I, KENNETH E. STUART, a citizen of the United States of America, residing in the city and county of Philadelphia, 5 in the State of Pennsylvania, have invented certain new and useful Improvements in Pneumatic-Despatch Systems, of which the following is a true and exact description, reference being had to the accompanying drawings, which form a part thereof.

My invention relates to pneumatic-despatch systems embodying two or more stations each equipped with directing mechanism whereby an approaching carrier is directed into one of two alternative paths, one of which carries it to the next succeeding station and in which selective mechanism connected with the carrier operating upon selective mechanism situated at the respective stations determines the path to be traveled by said carrier; and the object of my invention is to provide a novel construction of the selective devices whereby their range of operation is materially increased.

More particularly my invention is adapted for use in connection with and with a view of increasing the range of operation of selective mechanism described in my former application, filed January 27, 1902, Serial No. 91,312, in which each station is provided with a movable barrier extending into the path of the carriers and adapted in accordance with the operation of the selective mechanism either to yield to the impact of the carrier, permitting it to pass beyond the point at which the barrier is interposed, or, in the alternative, to remain in position, preventing the passage of the carrier and causing it to be deflected into the alternate path provided. In my said former application I showed and described in connection with barriers selective latching devices which in one position locked the barrier in position and in another position unlocked it, permitting it to be pushed out of the way by the carrier, these selective latching devices including fingers which project in front of the barrier to varying distances, so as to be engaged and operated by carriers having selective heads of a certain 45 character, while with other carriers having differently-formed selective heads the said

fingers were not engaged and the latching mechanism not operated.

My present invention consists in so constructing the latching devices and their fingers that the said fingers will in addition to extending to varying distances in front of the barrier extend also into the path of the carriers at varying distances from the center of the tube and in so constructing the selective 60 heads of the carrier as to provide them with circular engaging faces of varying depths and diameters, in this way and by the combination of the two selective systems greatly increasing the range of selective operation and 65 the possible number of stations among which the selection can be exercised.

Reference being now had to the drawings, in which my invention is illustrated, Figure 1 is a diagrammatic illustration of a pneumatic-despatch system equipped in accordance with my invention. Figs. 2, 3, 4, and 5 are plan views of carriers adapted for use in connection with my system and embodying my invention, and Figs. 6, 7, and 8 are views 75 illustrating the selective constructions of the latching devices.

A, A¹, A², A³, and A⁴ are a series of tube-sections connecting a series of intermediate stations (indicated at B', B², B³, and B⁴) with 80 a terminal despatching and receiving station, (indicated at B,) C indicating the open end of the tube A, into which carriers are inserted at the central station, D D, &c., indicating the intermediate station-heads, which, as shown, 85 are constructed in accordance with the devices described in my before-mentioned prior application, the incoming tube connecting with an arm D' of the head, which directs the carrier over a curved surface D² and directly 90 into an outlet-opening, (indicated at D³), the head being provided below said outlet-opening with a receiving-hopper D⁴, which connects with the next succeeding tube-section. The outlet-opening D³, as shown, is closed by 95 a gate or barrier E, which is hinged to the head at E' and has pivoted upon it at E² a lever having arms E³ E⁴, the arm E⁴ extending through an opening in the gate and forming the selective fingers upon which the carriers operate, while the arm E³ is arranged in 100 relation to a stop F, preferably elastic, so that

in one position it will engage said stop and prevent the opening of the gate, while in another position it will be free to move past the stop, permitting the gate to open under the impact of a carrier.

The end or finger of the lever-arm E^4 in my former construction extended to varying distances in front of the barrier or gate, as shown, for instance, in Figs. 6 and 7, and my present invention consists, mainly, in providing also for the extension of the finger E^4 into the tube in front of the barrier at varying distances from the center of the tube, as is clearly indicated, for instance, by contrasting Figs. 6 and 7, in which the fingers are in the center line of the tube, with Fig. 8, which illustrates the finger as extending into the tube at some distance from the center.

G G, &c., indicate the annulus at each station for the insertion of carriers, H H, &c., indicating the gates which normally close the annulus.

I is the head of the final receiving-station, I' indicating the outlet-passage for the carriers, and J the conduit connecting the final receiving-station with an exhaust fan or chamber.

K, K', K², and K³ illustrate the construction of selective heads adapted for use in connection with my invention and are simply given as typical, as the heads can obviously be varied through a very considerable range of construction. Thus in case of the carrier K (shown in Fig. 2) the head k' is provided with a shallow central orifice, (indicated at L,) while the other head (indicated at k²) is provided with a deeper central orifice (indicated at L') surrounded by a more shallow orifice, (indicated at L².) The carrier K' (shown in Fig. 3) is provided with one head, k³, having no orifice, while its other head is identical with the head k² of the carrier K and is similarly marked. In the case of the carrier K² (shown in Fig. 4) it is provided with one head, k⁴, having a central projecting portion L⁴, surrounded by an annular chamber L⁵, while its other head, k⁵, is formed with a broad shallow cavity, (indicated at L⁶.) The carrier K³ (shown in Fig. 5) has one head, k⁶, provided with a broad shallow cavity L⁷ and its other

head, k², similar to the head so marked in Figs. 2 and 3, and it will be obvious that with the illustrated construction of carriers and with appropriate variations in the selective lever-fingers a carrier can be directed into any one of a considerable number of intermediate stations.

In operation a carrier is introduced into the despatch-tube system with such selection as to its heads and as to its direction of introduction as would cause it to pass through any number of intermediate stations without actuating the unlatching mechanism until it reaches the station where it is designed for delivery and where it will come in contact with the determined selective lever-finger E⁴, unlatching the gate and permitting the exit of the carrier.

In all cases in the construction illustrated the carrier comes in contact with the barrier-gate; but in case the selective head has not acted upon the lever-finger E⁴ the gate remains closed and the carrier has its motion arranged so that it will fall into the hopper D⁴, but in reverse direction, turning end for end at each station at which it is delivered until, reaching the station arranged in advance, it engages and depresses the lever-finger E⁴, permitting the exit of the carrier.

Having now described my invention, what I claim as new, and desire to secure by Letters Patent, is—

In a pneumatic-despatch system including two or more stations having selective mechanism adapted to be actuated by selective heads on the carriers for determining the course of the carriers at said stations, the combination of selective fingers forming part of said mechanism and extending into the tube in the path of the carriers to varying distances and at varying distances from the center of said tube with a system of carriers having selective heads formed with circular finger-engaging faces of varying depth and of varying diameters.

KENNETH E. STUART.
